UNITED STATES PATENT OFFICE.

WILLIAM U. MOODY, OF POTTSVILLE, PENNSYLVANIA.

DESIGN FOR A GAME-BOARD.

SPECIFICATION forming part of Design No. 27,046, dated May 11, 1897.

Application filed March 18, 1897. Serial No. 628,225. Term of patent 31 years.

To all whom it may concern:

Be it known that I, WILLIAM U. MOODY, a citizen of the United States, residing at Pottsville, in the county of Schuylkill and State of Pennsylvania, have invented and produced a new and original Design for Game-Boards, of which the following is a specification, reference being had to the accompanying drawings, in which—

5 Figure 1 shows a plan view thereof; and Fig. 2, a sectional view of the same, taken on the line 2 2 of Fig 1.

10 The leading feature of my design consists of a rectangular base, as shown, and having 15 sectional partitions distributed thereon bent or shaped in the form of arcs of circles, the longer partitions being bent or curved in one and the same direction and the shorter ones, opposite the openings between said longer 20 partitions, bent or curved in the opposite direction, the central partitions being straight.

Referring to the drawings, A represents a rectangular base having in diagonally opposite corners thereof radial partitions *a* and having distributed around the center of said base sectional partitions B in the form of arcs of circles and curved in the direction as shown, and also shorter partitions C, opposite the spaces or openings between the shorter partitions, bent or curved in the opposite direction, the central or inner partitions D being straight.

Having fully described my invention, what I desire to secure by Letters Patent is—

The design for a game-board as herein shown and described.

WILLIAM U. MOODY.
